97,104

DESIGN FOR A MUSICAL INSTRUMENT BRIDGE, OR SIMILAR ARTICLE

Harry Stanley, Rocky River, and Vincent J. Moir,
Cleveland Heights, Ohio

Application June 26, 1934, Serial No. 52,348

Term of patent 14 years

To all whom it may concern:

Be it known that we, Harry Stanley and Vincent J. Moir, citizens of the United States and residents of Rocky River, county of Cuyahoga, and State of Ohio, and Cleveland Heights, county of Cuyahoga, and State of Ohio, respectively, have invented new, original, and ornamental Design for a Musical Instrument Bridge, or Similar Article, of which the following is a specification, reference being had to the accompanying drawing, forming a part thereof.

In the drawing:

Figure 1 is a perspective view of a musical instrument bridge, showing our new design;

Figure 2 is a cross-sectional view taken on the line II-II thereof; and

Figure 3 is an elevational view of the bridge of Figures 1 and 2.

The dominant feature of the design consists in the cross-sectional curvature of the top of the body or intermediate portion of the bridge.

We claim:

The ornamental design for a musical instrument bridge, or similar article, substantially as shown and described.

In testimony whereof, we hereunto affix our signatures, this 23rd day of June, 1934.

HARRY STANLEY.
VINCENT J. MOIR.
